ADJUSTING MECHANISM FOR FIREARMS

Miroslav Rolčík, Brunn-Husovice, Czechoslovakia, assignor to Československá Zbrojovka A. S. Brno, Brno, Czechoslovakia

Application June 20, 1936, Serial No. 86,414
In Czechoslovakia June 24, 1935

11 Claims. (Cl. 74—195)

My invention relates to mechanism for the continuous control of the speeds of two independent rotary movements without regard to the direction of rotation. It has particular reference to the control of means for adjusting fire arms on the tripod or other understructure both horizontally and vertically.

It is an object of my invention to provide means for effecting such adjustment of a fire arm in a particularly simple and efficient manner.

As is well known to those skilled in the art the adjusting mechanisms for effecting the sighting in correspondence with the calculated data both for elevation and for lateral displacement were hitherto operated manually or by means of a motor. Manual operation of the reversible adjusting mechanisms for fire arms, whether separately or simultaneously operated for horizontal and vertical adjustment, has been found to be unsuitable with fire arms serving to fire on fast moving objects. Manual operation requires the constant attention of the gunner and the speed of adjustment remains low. On the other hand adjusting mechanisms for fire arms, which are operated by a motor, are suitable only in connection with large guns, since they are greatly involved, quite especially if they comprise means for reversing as required in such a case.

It is important that the gunner, when operating such an adjusting mechanism, be only required to control a single member in order to be free to direct his attention solely to the observation of the object aimed at and to the firing proper, as only in such case a reliable operation of the fire arm and an efficient firing can be obtained.

According to the present invention I avoid the drawbacks connected with the means for adjusting fire arms as hitherto in use by driving the mechanisms for vertical as well as for horizontal adjustment from a single source of power, the power transmission from this source to the adjusting mechanism being effected by means of a transmission device which enables the speeds to be controlled continuously in both directions of rotation. The single components of the movements are controlled simultaneously, however independently from each other by means of a device common to both, which comprises two pivotally connected members which are arranged in the form of a self-contained unit in such manner as to enable two movements at right angles to each other to be controlled.

In the drawing affixed to this specification and

forming part thereof, a mechanism embodying my invention is illustrated diagrammatically by way of example.

In the drawing,

Fig. 1 is an axial section of the mechanism and the casing surrounding same, while Fig. 2 is a cross section on the line II—II in Fig. 1.

Referring to the drawing, 1 is the motor, 2 is the shaft transmitting power from the motor to a cogwheel 3 fixed on the motor shaft and 4 is another cogwheel supported in bearings 5 and meshing with the wheel 3. This pair of cogwheels transmits motion to the mechanisms for adjusting the fire arm in vertical and horizontal directions. In the example shown in the drawing power is transmitted by means of a friction gear. To this end the active faces 6 and 7 of the cogwheels are formed on separate plates 15, 16 seated in depressions formed in the wheels and acted upon by coil springs 17, projections 18 formed on the undersides of the plates 6, 7 extending into cavities formed in the wheel bodies to ensure the plates 6, 7 being carried along by the wheels. Friction discs 10 and 11 are in contact with the surfaces of plates 6 and 7, respectively, and rubber rings 12 and 13 mounted on the discs serve to create the necessary friction. The discs 10, 11 are mounted on shafts 20, 21 for axial displacement and secured against rotation thereon by keys 22, 23, thus carrying along the shafts. The discs 10 and 11 can be shifted to either side from their central position on the plates 6, 7.

The adjusting of the discs 10, 11 from their neutral position, independently from each other, and therewith the simultaneous adjusting of the respective speeds for both movements and opposite directions of rotation is effected by means of a device X operable with the aid of a single member.

This device is constituted mainly by a lever supported for oscillation on the tube 25 fixed to the casing 26. The shorter arm a of this lever is forked at 30 (Fig. 2), the arms of this fork projecting into an annular groove in an extension of the hub 31 of the friction disc 10. The hub of the lever is formed with two projections 33 forming bearings 34 for a journal 32, on which is rotatably mounted a double-armed lever Y, which can be rocked normally to the plane of rotation of the device X. On the short arm of lever Y is mounted a toothed segment 35 which meshes with a rack 36 formed on the extended hub 37 of the friction disc 11. Since the rack is

required to rotate together with the friction disc, its teeth are formed as rings.

A longer arm of the lever **Y** forms the handle **38** which serves to actuate the device **X**. Power 5 is transmitted from the shaft **20** to the horizontal adjusting means through the toothed wheel **40** (Fig. 2), while transmission of power from the shaft **21** for vertical adjustment is transmitted through wheel **44**.

10 If it is desired to manually adjust the gun, hand wheels **42** and **43** are mounted on the ends of the shafts **21** and **20**, respectively. In the case of manual operation contact between the friction discs **10** and **11** and the cogwheels **3**, **4**, respectively, is interrupted by suitable mechanism (not shown), which temporarily forces the plates **15**, **16** deeper into the depressions of the cogwheels **3**, **4**, respectively.

In order to adjust the gun the gunner controls 20 the vertical and horizontal adjusting mechanisms driven by the motor **1** by merely rocking the handle **38** in two directions at right angles to each other. With his other hand he operates the trigger. When sighting a predetermined object in accordance with the data furnished by 25 the observer the controlling member may advantageously be combined with an adjustment device for vertical and lateral adjustment.

On the other hand, when firing at quickly 30 moving objects observed by means of optical devices the movements of some of the parts of these devices may be transmitted by means of the power transmission device onto the controlling device **X** in order to simultaneously set operating 35 the adjusting mechanisms for vertical and horizontal adjustment.

While in the embodiment shown in the drawing and specifically described a friction drive mechanism has been illustrated, it is obvious 40 that other kinds of power transmission with continuous speed control, such as hydraulic, electric or other power transmissions, might be used. Similarly the details of the driving and controlling devices might be altered without departing 45 from the spirit of this invention or sacrificing the advantages resulting therefrom.

I wish it to be understood that I do not desire 50 to be limited to the exact details of construction shown and described for obvious modifications will occur to a person skilled in the art.

I claim:—

1. A mechanism for operating the means for vertically and horizontally adjusting fire arms comprising in combination a motor, two mechanisms operatively connected with said motor for driving the adjusting devices, means inserted between said motor and said mechanisms for continuously controlling the speeds in either direction of rotation and a device operatively connected with both mechanisms for simultaneously and independently controlling the components of such motion.

2. A mechanism for operating the means for vertically and horizontally adjusting fire arms 65 comprising in combination a motor, two mechanisms operatively connected with said motor for driving the adjusting devices, means inserted between said motor and said mechanisms for continuously controlling the speeds in either direction of rotation, said means comprising friction gearing, and a device operatively connected with both mechanisms for simultaneously and independently controlling the components of such motion.

75 3. A mechanism for operating the means for

vertically and horizontally adjusting fire arms comprising in combination a motor, two mechanisms operatively connected with said motor for driving the adjusting devices, means inserted between said motor and said mechanisms for continuously controlling the speeds in either direction of rotation, said means comprising a pair of cog wheels operatively connected with said motor and a pair of friction discs operatively associated with said cog wheels, and a device operatively connected with both mechanisms for simultaneously and independently controlling the components of such motion.

4. The mechanism of claim 3, in which a movable friction plate is associated with each cogwheel and its respective friction discs and a spring is inserted between each wheel and plate.

5. The mechanism of claim 3, in which the controlling mechanisms comprise shafts for driving the vertical and lateral adjusting devices, 20 said shafts carrying the friction discs for axial displacement, and further comprise means for simultaneously, but independently controlling said discs.

6. The mechanism of claim 3, in which the controlling mechanisms comprise shafts for driving the vertical and lateral adjusting devices, 25 said shafts carrying the friction discs for axial displacement, and further comprise means for simultaneously, but independently controlling 30 said discs, said controlling means being arranged coaxially with and rockably on one of said shafts.

7. The mechanism of claim 3, in which the controlling mechanisms comprise shafts for driving the vertical and lateral adjusting devices 35 and carrying the friction discs for axial displacement, said adjusting devices comprising a lever for simultaneously, but independently controlling said discs, and a fork on said lever which fork is operatively connected with one of said 40 discs for displacing same in one or the other direction for reversal and change of speed of rotation.

8. The mechanism of claim 3, in which the controlling mechanisms comprise shafts for driving the vertical and lateral adjusting devices, 45 said shafts carrying the friction discs for axial displacement, said adjusting devices comprising a lever for simultaneously, but independently controlling said discs, and a fork on said lever 50 which fork is operatively connected with one of said discs for displacing same in one or the other direction for reversal and change of speed of rotation, and a second lever oscillatable about an axis at right angles to said first lever and operatively connected with said other disc for displacement at right angles to said other disc.

9. The mechanism of claim 3, in which the controlling mechanisms comprise shafts for driving the vertical and lateral adjusting devices, 60 said shafts carrying the friction discs for axial displacement, the adjusting devices comprising a lever rockable about one of said shafts for simultaneously, but independently controlling said discs.

10. A mechanism for operating the means for vertically and horizontally adjusting fire arms comprising in combination a motor, two mechanisms operatively connected with said motor for driving the adjusting devices, friction means inserted between said motor and said mechanisms for continuously controlling the speeds in either direction of rotation, and a double-armed lever subdivided in two parts, arranged for oscillation 70 at right angles to each other, both parts being 75

rockable about the axis of one of said driving mechanisms and each part operatively engaging one of said friction means for adjusting same.

5 11. A mechanism for operating the means for vertically and horizontally adjusting fire arms comprising in combination a motor, two mechanisms operatively connected with said motor for driving the adjusting devices, means inserted between said motor and said mechanisms for continuously controlling the speeds in either direction of rotation, said means comprising a pair of

cogwheels operatively connected with said motor and a pair of friction discs operatively associated with said cogwheels, shafts extending at right angles to each other, each carrying one of said friction discs, a lever oscillatably mounted on one of said shafts for displacing one of said discs on the other shaft and another lever pivoted to said first lever for oscillation at right angles to it for displacing the other disc on said one shaft.
